UNITED STATES PATENT OFFICE

170,055

TIRE

Earle W. Hawkinson, Minneapolis, Minn., assignor
to Paul E. Hawkinson Company, Minneapolis,
Minn., a corporation of Minnesota

Application June 19, 1952, Serial No. 20,269

Term of patent 14 years

(Cl. D90—20)

To all whom it may concern:

Be it known that I, Earle W. Hawkinson, a citizen of the United States, residing at Minneapolis, county of Hennepin and State of Minnesota, have invented a new, original, and ornamental Design for a Tire, of which the following is a specification, reference being had to the accompanying drawing, forming a part thereof.

The figure is an elevational view of a tire showing my new design.

I claim:

The ornamental design for a tire, as shown.
EARLE W. HAWKINSON.
